UNITED STATES PATENT OFFICE

CHARLES B. JOHNSON, OF CHICAGO, ILLINOIS

INSULATING CLAMP

Application filed July 9, 1928. Serial No. 291,372.

My invention relates to insulating clamps and the like and as a specific form of application consists of a thin plate-like structure which is of use in connection with apparatus 5 designed for the purpose of permanently waving human hair. This plate-like structure consists of a pair of movable elements so that an indefinite amount of hair may be clamped between the movable sections, the 10 plate-like structure itself resting against the head so as to form an insulating barrier to prevent heat from the heaters which are utilized in the curling operation from affecting the scalp.

15 In one of its forms, the structure is also designed so that it may clamp the hair sufficiently tight so that moisture from the heaters is prevented from reaching the scalp.

My invention has a plurality of uses but 20 I will describe the specific form above indicated more in detail by referring to the accompanying drawings in which—

Fig. 1 is a plan view of a clamp constructed in accordance with my invention;

25 Fig. 2 is a similar view showing the parts in their alternative position;

Fig. 3 is a similar view showing the device clamping a bundle of hair;

30 Fig. 4 is a sectional view on line 4—4 of Fig. 5 showing the parts in their retracted position; and

Fig. 5 is a sectional view on line 5—5 of Fig. 4.

35 In the form shown, my device consists of two thin plate-like elements 10, 11, these elements 10 and 11 having finger holds 12 and 13 respectively. These two plates are held in relatively fixed relationship and carry between them a third plate-like element 14 shown more clearly in Fig. 4. The elements 10 and 11 are held in their fixed relationship by the bolts or rivets or other suitable fastening means 15, 16 and a third fastening 40 element 17 holds all three elements 10, 11 and 14 in pivotal relationship.

A spring 27 finding a support upon the fastening means 15 has its free extremity 18 urging the element 14 in a counterclockwise direction (see Fig. 4). The other free extremity 50

19 of the spring is anchored in the plate 10 for purposes that are obvious.

The plates 10 and 11 are provided with a suitable slot 20 which extends radially from the periphery to the center of these plates where this slot is preferably enlarged to form a more or less circular hole. The slots 20 and holes 21 in the two plates 10 and 11 are superposed as shown. The element 14 has at its intermediate portion a rounded cutaway section 22 so that when this element is in its retracted position as shown in Fig. 4 the hole 21 constitutes an unobstructed opening through the three plates 10, 11 and 14. The element 14 is provided with a finger hold 23 as shown. In using the device as shown in Fig. 1, the finger holds 12, 13 and 23 are grasped and the device opened into the position as shown in Fig. 2. The desired quantity of hair may then be introduced through the slot 20 into the hole 21 and the pressure on the finger holds is released so that the spring 27 may force the device so that its respective elements occupy the positions shown in Fig. 3 with the bundle of hair 24 clamped tightly together.

It will be apparent that the circumferential portion 25 of the element 14 is then in position to entirely close the slot 20 and also the hole 21 with the exception of that portion occupied by the hair. The clamp when in position upon the scalp rests snugly against the scalp and it is a prime desideratum of a device of this kind that it be extremely thin so that the hair may be waved or curled to a point as close to the scalp as possible. The edge of the material about the hole 21 may be corrugated if desired.

From what has been thus described, the nature of my invention will be readily clear to those skilled in the art and it will also be apparent that modifications may be made without departing from the spirit of my invention.

What I claim as new and desire to secure by Letters Patent is:

1. A clamp of the character and for the purposes specified comprising a pair of spaced plate-like superposed elements having aligned radial slots, and a third plate-like element 10

swingly mounted between said first aforesaid elements and adapted in one limiting position to open said slots and in its other limiting position to close said slots, said elements having means to clamp unlike portions of material interiorly of their periphery and simultaneously to close the unoccupied portion of said slots, said third element being cut away at one side whereby to leave 10 an open space between said pair of elements adjacent the material being clamped to permit free access of air to the clamped material.

2. A hair clamp for hair waving comprising 15 a pair of spaced thin heat insulating disks having aligned slots extending inwardly from their peripheral edges, said slots being enlarged at their inner ends, and a plate-like element swingingly mounted between said disks movable across said slots to clamp hair in the inner ends thereof, said element lying wholly on one side of a line through said slots when in open position to permit air circulation between said disks adjacent the hair therein for cooling the same.

3. A hair clamp for hair waving comprising 20 a pair of spaced thin heat insulating disks having aligned slots extending inwardly from their peripheral edges, said slots being enlarged at their inner ends, and a plate-like element swingingly mounted between said disks movable across said slots to clamp hair in the inner ends thereof, said element lying 25 substantially wholly on one side of the hair clamped in said slots to permit air circulation between said disks adjacent the hair therein for cooling the same, and spring means urging said member into hair clamping position.

40 4. A hair clamp for hair waving comprising 25 a pair of spaced thin heat insulating disks having aligned slots extending inwardly from their peripheral edges, said slots being enlarged at their inner ends, and a plate-like 30 element swingingly mounted between said disks movable across said slots, to clamp hair in the inner ends thereof, said element lying substantially wholly on one side of the hair clamped in said slots to permit air circulation 35 between said disks adjacent the hair therein for cooling the same, and a spring having one end fixed relative to said disks and the other end engaging said member and pressing it toward its clamping position.

55 5. A hair clamp for hair waving comprising 35 a pair of spaced thin heat insulating disks having aligned slots extending inwardly from their peripheral edges, said slots being enlarged at their inner ends, and a plate-like 40 element swingingly mounted between said disks movable across said slots to clamp hair in the inner ends thereof, said element occupying less than half the space between said disks whereby to permit air circulation 45 between said disks adjacent the hair therein

for cooling the same, spring means urging said member into clamping positions, and projections on said member, and disks forming finger pieces for moving said member against the pressure of said spring means.

6. A hair clamp for hair waving comprising 50 a pair of spaced thin heat insulating disks having aligned slots extending inwardly from their peripheral edges, said slots being enlarged at their inner ends, and a plate-like element swingingly mounted between said disks and lying within the periphery thereof movable across said slots to clamp hair in the inner ends thereof, said element lying wholly on one side of a line through said slots when in open position to permit air circulation between said disks adjacent the hair therein for cooling the same.

In witness whereof, I hereunto subscribe my name this 22nd day of June, A. D. 1928.

CHARLES B. JOHNSON.
